UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

DESIGN FOR A VEHICLE LAMP.

Application filed November 21, 1924. Serial No. 11,441. Term of patent 14 years.

To all whom it may concern:

Be it known that I, CHARLES E. GODLEY, a citizen of the United States, residing at Detroit, in the county of Wayne and State of Michigan, have invented a new, original, and ornamental Design for a Vehicle Lamp, of which the following is a specification, reference being had to the accompanying drawing, forming part thereof.

In the drawings, Fig. 1 is a front elevation of a vehicle lamp, showing my new design.

Fig. 2 is a side elevation of the same.

I claim:

The ornamental design for a vehicle lamp, as shown.

CHARLES E. GODLEY.
